UNITED STATES PATENT OFFICE.

HERMAN WATSON OSBORN, OF BEDFORD, OHIO.

DESIGN FOR A TIRE TREAD.

61,102.

Specification for Design. Patented June 20, 1922.

Application filed October 27, 1921. Serial No. 510,971. Term of patent 14 years.

To all whom it may concern:

Be it known that I, HERMAN W. OSBORN, a citizen of the United States of America, residing at Bedford, in the county of Cuyahoga and State of Ohio, have invented a new, original, and ornamental Design for a Tire Tread, of which the following is a specification, reference being had to the accompanying drawing, forming part thereof, in which—

Figure 1 is a plan view of my present design embodied in an automobile tire tread or casing; and

Figure 2 is a transverse sectional view taken on the line 2—2 of Figure 1.

It is to be understood, however, that my

said ornamental design is applicable not alone to tire treads or casings, but is intended, and is equally well suited for the ornamentation of similar articles of manufacture having surface ornamentation, without in the least departing from my invention.

I claim:

The ornamental design for a tire tread as shown.

In testimony whereof I subscribe my signature in the presence of two witnesses.

HERMAN WATSON OSBORN.

Witnesses:

E. W. BOYER,

GEO. H. BOYER.
